His Attorney.

UNITED STATES PATENT OFFICE.

HARRY F. PERKINS, OF SCHENECTADY, NEW YORK, ASSIGNOR TO GENERAL ELECTRIC COMPANY, A CORPORATION OF NEW YORK.

VAPOR ELECTRIC DEVICE.

1,240,772.

Specification of Letters Patent. Patented Sept. 18, 1917.

Application filed April 14, 1915. Serial No. 21,271.

To all whom it may concern:

Be it known that I, HARRY F. PERKINS, a citizen of the United States, residing at Schenectady, county of Schenectady, State 5 of New York, have invented certain new and useful Improvements in Vapor Electric Devices, of which the following is a specification.

The present invention relates to the construction of vapor electric devices and particularly to metal-walled high-powered mercury arc rectifiers.

In the operation of electric arc devices containing a vaporizable material, such as 15 mercury, a conducting material is found to deposit on relatively cool parts of the interior exposed surfaces of the apparatus. This material appears to consist partly of oxidized mercury and partly of impurities 20 but whatever its nature this deposit is conducting and is a source of trouble in the operation of the rectifier. Condensed mercury is also deposited on insulating surfaces especially when the device is cold as at starting.

I have found that the conducting material is deposited in some manner by the vapor blast and that when projections or barriers on the interior surface of the device 30 extend transversely to the vapor blast that a part of the surface is thereby shielded from the deposit.

In accordance with my invention insulators within the rectifier are provided with 35 shielding devices, such as ridges or convolutions in the recesses of which the conducting material will not be deposited, thus insuring clean bands or zones on the surface of the insulation.

40 In the accompanying drawing Figure 1 is an outline view of the vapor device showing the relation of the various parts; Fig. 2 is a detail sectional view of one form of cathode seal embodying my invention; Fig. 45 3 is a sectional view of another form of seal.

One form of vapor electric apparatus, to which my invention is particularly applicable, is the metal-walled mercury arc rectifier shown in general outlines in Fig. 1. The device consists of a main arc chamber 1 containing main anodes 2, 2' surrounded by 50 hoods 3, 3' and a starting anode 4. The main chamber 1 communicates with a chamber 5 containing the cathode. The electrode

seals have been merely indicated, and for a more complete description of a form of mechanical seal and other structural details suitable for a metal-walled evacuated container, reference may be had to U. S. Patent 60 No. 1,118,380 to W. E. Story.

A cathode chamber is shown in greater detail in Fig. 2, the clamping devices for holding together the parts of the cathode seal being omitted, and the bottom plate 8 being shown broken away. The lower wall 9 of the cathode container consists of metal. It is separated from the plate 8 by a section of insulation 7 and bears against a section 10 of porcelain or other suitable inert, gas-tight insulation. Washers 11 consisting of aluminum, copper, asbestos or other compressible material are interposed between the insulating section 10 and the adjoining parts 1 and 9 respectively. The insulating section 10 is provided on its inner surface, as indicated, with a series of projecting convolutions or ridges 12 substantially parallel to the surface of the body of mercury 13 and interposed in the path of the arc blast 75 emanating from the mercury cathode 13. I have found in practice, when the insulating sections are thus provided with outwardly projecting barriers or ridges, that the recess or hollows between the ridges remain free 80 from conducting deposit, the ridges casting "shadows" on the insulating surfaces when subjected to the vapor blast.

In Fig. 3 the entire cathode container 14 consists of insulating material. It is anchored in place by the projecting lugs 15 attached to the sides of the outer metal cup 16 of the cathode. This metal cup 16 is attached to the main body 1 of the vapor device by means of bolts 17 or in any other 90 suitable manner, a washer 18 being interposed to make a vacuum-tight seal. Electrical connection may be made with the cathode 13 through a rod 19 projecting through the side of the cathode chamber 100 and having at its end a depending conductor 20 dipping into the mercury. The terminal 19 is surrounded by an insulating tube 21. The rods 22 which are screwed into the flange 23 and serve to attach the current conveying terminal to the body of the rectifier have been merely indicated as this structure is not part of my present invention.

The mercury evaporated from the cathode 13 and condensed in the upper part of the 110

rectifier is returned to the annular space between the cathode cup 14 and the metal wall of the cathode container and this mercury drains back into the cathode cup 5 through a sloping orifice 24. The ridges on the surface of the cathode cup assist in breaking up the mercury stream into drops so as to prevent a short circuit between the cathode and the metal wall of the cathode 10 chamber.

What I claim as new and desire to secure by Letters Patent of the United States, is,—

1. A vapor electric device comprising a metal container, a vaporizable cathode, one 15 or more coöperating anodes, and means for electrically insulating the cathode from the main part of the container, said insulating means having a plurality of ridges extend-

ing transversely between the cathode and the anode or anodes.

2. A vapor electric device comprising a mercury cathode, one or more coöperating anodes and an inclosing envelop, the cathode-containing part of said envelop consisting at least in part of insulating material, 25 the surface of which is provided with annular protuberances.

3. In a vapor arc device, a mercury cathode and a container therefor consisting in part at least of porcelain and having a plurality of ridges located on the surface of the container above the mercury surface and substantially parallel thereto.

In witness whereof, I have hereunto set my hand this 13th day of April, 1915.

HARRY F. PERKINS.
